UNITED STATES PATENT OFFICE.

JOSEPH E. FAWELL, OF PITTSBURGH, PENNSYLVANIA.

ROLLING MILL.

Application filed March 30, 1922. Serial No. 548,028.

To all whom it may concern:

Be it known that I, JOSEPH E. FAWELL, residing at Pittsburgh, in the county of Allegheny and State of Pennsylvania, a citizen of the United States, have invented or discovered certain new and useful Improvements in Rolling Mills, of which improvements the following is a specification.

10 In the operation of three high mills as now constructed, it is necessary to employ vertically movable feed tables because the article being rolled is fed to and received from the rolls in different horizontal planes. 15 Such tables are expensive to build not only on account of the necessity employing lifting mechanisms, but also on account of making provision for operating the feed rollers in the different positions of the 20 tables. Furthermore, the employment of manipulators in connection with such vertically movable tables adds greatly to the expense of installation and maintenance.

The invention described herein has for 25 one of its objects a construction of a three high mill, permitting of the feeding of the article being rolled in the same horizontal plane for both the back and forth passes, such end being attained by mounting the rolls 30 in a vertically movable housing and the operation of the manipulating mechanism by and in accordance with the movement of the housing.

The invention has for it further object 35 the provision of an improved manipulator for such rolls. The invention is hereinafter more fully described and claimed.

In the accompanying drawings forming a part of this specification, Fig. 1 is a side 40 elevation of a three high mill embodying the improvements claimed herein; Fig. 2 is a sectional plan view of the same; Figs. 3 and 4 are a sectional elevation on a plane indicated by the line III—III, Fig. 2 illustrating alternate positions of the parts shown.

In the practice of the invention, the housing 1, which is provided with windows, as is customary, in which are mounted the 50 bearings for the support of the different rolls, is movably mounted in the frame consisting of a base plate 2 supported on a suitable foundation and vertical posts or uprights 3 adapted to serve as guides for 55 the housing in its vertical movement. In the construction shown, the posts are pro-

vided with ribs 4 adaptable to engage grooves in the vertical members of the housing 1. In order that scale, etc., shall not interfere with the vertical movement 60 of the housing, an opening is made through the base to permit the scale to drop into a pit 6 arranged in the foundation of the mill. Any suitable means may be employed whereby a vertical movement of the housing may be effected. In the construction shown, the shifting mechanism consists of a motor, for example, a fluid pressure cylinder 7, preferably hydraulic, and provided with a ram 8 to which 70 is secured a head 9 provided with trunnions 10 for the reception of the eyes at one end of the pitmen 11 which have their opposite ends connected to an arm 12 on a shaft 13 mounted in suitable bearings carried by the 75 base 2. This shaft 13 is provided with arms 14, and the ends of these arms 14 are pivotally connected to struts 15 having their upper ends arranged in bearings 16 on the underside of the housing 1.

As the housing and the rolls mounted therein will always be sufficiently heavy to insure their downward movement when permitted by the escape of fluid from the cylinder 7, the latter is made of a single acting 85 character and is employed merely for raising the housing. Suitable means are employed to prevent the too rapid downward movement of the housing, such for example as that shown, consisting of the cylinder 17. 90

In the construction shown, the controlling cylinder 17 either has its outer end opened or is provided with an escape port permitting the free outward flow of air when the piston moves to the left, and with a 95 port controlled by a valve of any suitable construction, and indicated at 19, which will control the escape of air as the piston is drawn to the right by the downward movement of the housing. This controlling mechanism may be so constructed in proportion relative to the downward movement of the housing that when the housing is in the desired down position, the piston will bear against the right hand end of the cylinder and hold the housing from further movement. It is preferred, however, to limit the downward movement of the housing by means of lugs 1^a formed on the sides 100 of the housing and adapted to bear on the vertical guide posts 3 of the frame when the housing is in its lowered position. It

is preferred that the housing should be counterbalanced, as for example by a weight 27 mounted on an arm 28 secured to the shaft 13.

5 Feed tables, having rolls adapted to be driven in reverse directions so as to effect a movement of the article being rolled towards and from the rolls, are arranged on opposite sides of the mill and the side frames 10 21 of these tables are supported by foundations, the inner ends of the frames being preferably supported in such manner as to insure the proper relation between the rollers and the bite of the rolls by brackets on the 15 vertical members 3 of the guide frames. These feed tables are preferably of the construction usually employed in a two high reversing mill. These feed tables are arranged so that a plane tangential to the 20 upper side of the table rollers 20 will be approximately tangential also to the top of the reducing surface of the lower roll in the housing when the latter is raised as shown in Fig. 1, and the housing shifting mechanism 25 is so constructed and adjusted that the vertical movement of the housing will be substantially equal to the diameter of the middle roll so that when the housing is lowered, a plane tangential to the top of the 30 feed rollers will always be approximately tangential to the top of the middle roll.

While any suitable form of manipulator may be used or combined with the mill, it is preferred to use a manipulator such as is 35 illustrated in Figs. 1, 2 and 3, inclusive, which operates in coordination with the movements of the roll-housing both to shift blanks laterally or across the rolls and to turn them. The manipulator comprises buggies 30 mounted on rails 31 parallel, or substantially parallel, with the axes of the feed rolls. The buggies are provided with standards 32 projecting up between the feed rolls 20 and having a plurality of guide bars 33 40 attached to them extending transversely of the feed rolls. The buggies are connected by rods 34 to bell-crank levers 35 which may be pivotally mounted on supports 36 to operate in horizontal planes. These levers 45 are attached to a rod 38 which in turn is connected by a link 39 to the arm 12; so that the vertical movement of roll-housing causes the buggies to move from one to the other of their alternate positions, shown in Figs. 50 3 and 4.

To turn a billet or other article being rolled, fingers 40 are mounted for vertical reciprocation in the guide-bars 33. The lower ends of these fingers are attached by 55 links 41 to bell-crank levers 42 pivoted to arms 43 attached to the buggies. The other arms of these bell-crank levers are connected to rods 44 pivotally secured to the side frames 21 of the feed tables.

55 In the operation of the mill the roll hous-

ings are moved vertically by means of the fluid pressure cylinder 7 and the levers and links connected to it, both for the purpose and in the manner already explained. In using the manipulator, the first pass of the 70 blank may be between the right hand ends of the lower and intermediate rolls as viewed in Fig. 3, the pass being from the manipulator side of the rolls. When the rolls are lowered, the blank being on the other side 75 of the rolls, the manipulator is simultaneously moved to the position that the blank will be received between the second and third guide bars from the right hand end. Raising the rolls for the third pass, moves the manipulator to the left, and as it so moves, the fingers 40 rise under the right hand end of the blank and turn it. This operation is repeated for all the roll passes, or modified according to the desired sequence of passes. 80

It is characteristic of the improvement claimed herein that only one member of the mill need be shifted to effect back and forth passes, whereas in three-high mills heretofore constructed, both tables had to be vertically shifted for the several passes and such tables had to be supported at the pivotal points and the point of connection with the shifting mechanism without an intermediate support; the frames of the tables had to be 85 made heavy and strong, whereas in the construction claimed herein the tables are supported throughout their entire length by a solid foundation, and the frames can be made very much lighter. 90

The invention described herein is not limited, as regards the broader claims, to a mill having three vertically arranged rolls as a larger number of rolls can be arranged in the housing, and the movement of the latter controlled accordingly. My invention contemplates the employment in a mill of a housing vertically movable with reference to a stationary feed table and having in such housing bearings for a plurality of vertically arranged rolls, i. e., rolls having their axes in or approximately in the same vertical plane, and the provision of a manipulator for such a mill. 105

110 I claim herein as my invention:

1. In a rolling mill the combination of a vertically movable housing, upper, lower, and intermediate rolls carried by said housing, a vertically stationary feed table, a manipulator, and coordinated mechanism 115 for simultaneously shifting the housing vertically with reference to the feed table and for operating the manipulator.

2. In a rolling mill the combination of a vertically movable housing, upper, lower, 120 and intermediate rolls carried by said housing, a vertically stationary feed table, means for shifting the housing vertically with reference to the feed table, a manipulator for moving blanks across the rolls and for si- 125 130

multaneously turning the blanks, and means coordinate with the housing shifting means for operating the manipulator.

3. In a rolling mill the combination of a frame having vertical guide members, a housing movably arranged in said frame, upper, lower, and intermediate rolls carried by said housing, a shaft provided with arms extending under the housing for moving it vertically, stationary feed tables arranged

on opposite sides of said frame, a manipulator arranged with one of said tables for moving blanks across the rolls and for simultaneously turning the blanks, and a motor connected to said shaft and to said manipulator for simultaneously turning the shaft and operating the manipulator. 15

In testimony whereof, I have hereunto set my hand.

JOSEPH E. FAWELL.
